(57) **CLAIM**

The ornamental design for a paint tray, as shown and described.

DESCRIPTION

FIG. 1 is a perspective view of a paint tray;
FIG. 2 is a front elevational view of the paint tray;
FIG. 3 is a top plan view of the paint tray;
FIG. 4 is a right elevational view of the paint tray;
FIG. 5 is a rear elevational view of the paint tray;
FIG. 6 is a bottom plan view of the paint tray; and,
FIG. 7 is a left elevational view of the paint tray.
The broken lines shown in the drawings depict portions of
the paint tray that form no part of the claimed design.
